US00D945615S

(12) **United States Design Patent** (10) Patent No.: **US D945,615 S**
(45) Date of Patent: **** Mar. 8, 2022**

(54) **MEDICAL LASER FOR DISC
DECOMPRESSION SURGERY**

(71) Applicant: **REV-MED, INC.**, Seongnam-si (KR)

(72) Inventors: **Bong Geun Shin**, Suwon-si (KR);
Yong Man Cho, Seoul (KR)

(73) Assignee: **REV-MED, INC.**, Seongnam-si (KR)

(**) Term: **15 Years**

(21) Appl. No.: **35/510,091**

(22) Filed: **Dec. 11, 2019**

(80) **Hague Agreement Data**

Int. Filing Date: **Dec. 11, 2019**

Int. Reg. No.: **DM/209737**

Int. Reg. Date: **Dec. 11, 2019**

Int. Reg. Pub. Date: **Aug. 21, 2020**

(30) **Foreign Application Priority Data**

Dec. 10, 2019 (KR) 30-2019-0059756
